UNITED STATES PATENT OFFICE.

FEDERICO VIOLATI-DESCARI, OF ARIANO, ITALY.

STEAM-PLOW.

No. 903,032.

Specification of Letters Patent.

Patented Nov. 8, 1908.

Application filed April 27, 1907. Serial No. 370,688.

To all whom it may concern:

Be it known that I, FEDERICO VIOLATI-DESCARI, farmer, subject of the King of Italy, residing at Ariano, Polosinc, Italy, 5 No. 2 Via Umberto 10, have invented new and useful Improvements in Steam-Plows, of which the following is a specification.

My invention relates to improvements in steam plows, and the object of my invention 10 is to provide simple means for plowing land by power.

Steam plows operated directly or indirectly by traction have hitherto been used, but some, at least the systems employed required very powerful, heavy and expensive machinery. In said systems a gang of plows was usually used, which system was open to the objections that the ground was often times not thoroughly plowed, the plows were liable to become clogged up with grass and stubble, and could only be operated very slowly. Furthermore, such systems were difficult to operate, more especially on account of the difficulty in turning and required 25 heavy and expensive special machinery.

Many farmers have at their disposal a portable steam engine of six or eight horse power, more especially used in harvest time, while for the remainder of the year it remains inactive.

The object of the present invention is to provide a light and cheap system of mechanical plowing, using engines which many farmers already have, the special feature being that it can be worked continuously, as no time is lost in turning at the end of the furrow.

With the objects stated in view, my invention consists in the construction and combinations of parts as hereinafter described and claimed.

In the accompanying drawings—Figure 1 is a diagrammatic view of the entire system. Fig. 2 is an end view, partly in section, of the truck carrying the plows. Fig. 3 is a side view of the same, partly in section. Fig. 4 is a plan view of the truck, parts being broken away. Figs. 5 and 6 are enlarged views showing details of the truck. Fig. 7 is a side view of the windlass and supporting frame. Fig. 8 is an end view of the same. Fig. 9 is a broken top plan view of the same. Fig. 10 is a cross sectional view, showing the operating pulleys and connections. Fig. 11 is a cross section of the winding drums. Fig. 12 is a side of

the brake operating and belt shifting mechanism. Fig. 13 is a perspective view, on an enlarged scale, of one of the rope or cable holders, and Fig. 14 is a top plan view of one of the guiding pulleys.

Referring to Fig. 1, *a* represents the engine which is connected by a belt *b* with the winding mechanism *c*, from which runs the continuous cable *d* over the pulleys *e*, *f*, *g*, *h*, supported in proper relation in the field to be plowed by means of the ordinary braced supports, such as *i*. *j* represents the truck carrying the plows. This truck consists of a rectangular frame composed of the parts *k*, *m*, *n* and *o* firmly united together. Pivotally mounted in the top *k* and the bottom *n* of this frame, is the rotatable shaft *p*, which carries the plow beam. This shaft is provided near its lower end, with a gear wheel *q*, a rectangular portion *r* provided with a rectangular recess *s*, a supporting block *t* adjustably fastened to the shaft by the screw *u* and the supporting block *v* having a dome shaped top *w* on which the plow beam *x* rests, this plow beam being slotted so that it can easily move upon the shaft *p*.

The truck is adjustably supported by three wheels, one large one arranged on one side of said truck and two small ones arranged as a pair on the other side of said truck. The large wheel *y* is arranged to travel in the furrow made and is adjustably secured on its shaft *1*, which is screw-threaded and is held in any desired position upon said shaft by nuts *2*. The shaft *1* is, at its inner end, bent upward, as shown at *3*, and is provided with clips *4* and encircles the side *m* of the frame.

Attached to the upper end of the part *3* is a screw *5* which passes through a screw-threaded opening in the side *k* of the frame, and this screw is provided with a hand wheel *6* at its upper extremity, by the movement of which hand wheel, the wheel *y* may be moved up and down to vary the depth of the furrow.

Opposite the wheel *y* is a frame *7* adjustably secured by means of clips, such as *8*, to the side *o* of the frame. The frame *7* is provided with horizontally extending axles, such as *9*, on which are mounted the small wheels *10*. To one of the clips *8* is pivotally attached a screw rod *11* terminating in a hand wheel *12*, which rod passes through a screw-threaded opening in the part *k* of the frame. Obviously by turning the hand

wheel 12 the frame 7 may be adjusted up and down, carrying with it the small wheels 10, such adjustment being necessary to keep the small wheels in proper relation to the large wheel *y*.

Fastened to the plow beam *x* are two platforms 13 and 14 and carried on the frame 7 above the wheels 10 is a third platform 15, which latter is merely used to enable the operator to step from one of the platforms on the beam to the other.

The plow beam *x*, as shown, is arranged to tilt freely upon the shaft *k*, and it is provided near each end with a plow share 16 and a cutting knife 17, of any desired or preferred type.

Seats 18 and 19 for the driver are pivotally mounted in the plow beam *x*, and the supporting standards 20 and 21 of these seats pass through the plow beams, being pivoted thereon by pins, such as 22. The lower ends of these arms are connected to links 23 and 24, the inner ends of which are pivotally connected to an annular bracket 25 which is arranged to fit in the recess 26 in the block *v*. Obviously from the construction described, as the plow beam moves up and down the seats 18 and 19 will be tilted, for a purpose hereinafter explained.

27 represents a rod passing down through a perforation in the part *k*, and having its lower end pivotally mounted in the part *n* of the frame. This rod is provided with a large hand wheel 28 at its top and with a gear pinion 29 near its lower end, which gear wheel meshes with the gear wheel *q* on the shaft *p*. Obviously by the movement of the wheel 28 the shaft *k* will be moved and will carry with it the plow beam *x*, thus varying the draft upon the plow and regulating the width of the furrow cut.

Attached to the upper edge of the part *k* of the frame, are springs 30 and 31, and attached to the plow beam is a curved brace 32 which passes between said springs, the tendency of which is to prevent vibration of the plow beam and to always return the parts into the position shown in Fig. 2.

The cable *d* is not attached directly to the plow beam, but indirectly thereto, by the following means. The end of this cable is attached to a securing device 33, shown on an enlarged scale in Fig. 13. From this device 33 a chain 34 leads, which is attached to one end of an arm 35 of a deviator, the other arm 36 of which is bent at an angle thereto, the two arms being united together by a brace 37 for the purpose of giving additional strength to the structure. The other end of the arm 36 is fastened to a block 38 carried on one end of a rectangular bar 39, which bar is adapted to slide through the recess in the projection *r* of the shaft *p*. The bar 39 has attached to it, at its other end, a similar block 40, to which is attached

an arm 41 of the other draft device, to which the other end of the cable *d* is secured, the construction being the same at each end of the truck. To the block 38 are attached two chains 42 and 43 which run up to, and are engaged by hooks on the platform 14. Similarly two chains 44 and 45 run up from the block 40 to hooks on the platform 13. Obviously a pull in the one direction or the other upon the cable *d* will first pull the bar 39 through the projection *s* until one of the blocks on said bar strikes the part *r* and during this motion of the bar 39 the plow beam will be tilted into the position shown in Fig. 3, for example (or the reverse position) by means of the supporting chains fastened to the platform, and the seats 18 and 19 will be moved so as not to strike the wheel 28.

The winding mechanism *c* will next be described. This mechanism is mounted upon a heavy frame composed of sides 46 and 47 and ends 48 and 49. This frame is supported on wheels 50 and 51 mounted on stub axles 52 and 53 carried by the sides 46 and 47. 54 represents a pole by which the frame may be dragged from one place to another, said pole being easily detached from the end beam 49.

On the beam 48 is mounted a supporting bracket carrying an adjusting screw 55 provided with a hand wheel 56, 57 representing a support adapted to be placed upon the ground and having a central depression adapted to receive the end of the screw rod 55. To each end of the beams 46 and 47 is attached a rectangular loop 58.

In setting up the winding mechanism it is dragged to the desired place while still mounted on the wheels 50 and 51. The pole 54 is then removed and the frame tipped until the pole-carrying end thereof rests upon the ground. The screw rod 55 is then operated to lift the wheels 50 and 51 off of the ground, and these wheels are then removed. The rod 55 is then again operated, lowering the whole frame to the ground, when stakes are firmly driven into the ground through the loops 58, thus anchoring the frame firmly. This frame carries the winding mechanism which will now be described.

Upon the side beams 46 and 47 are mounted approximately triangular frames 59 and 60, each of said frames being an open casting composed of two sides and a cross piece, such as 61. Mounted in the center of these cross pieces is the shaft 62, on which the winding drums 63 and 64 are supported. The winding drum 63 is keyed directly to the shaft 62, but the winding drum 64 is loosely mounted on said shaft being carried by a sleeve 65. See Fig. 11. The drum 63 has secured to it a gear wheel 66 and the drum 64 has secured to it a gear wheel 67, and each of these drums has a projecting

portion leaving a recess, such as 68, through which a brake strap passes.

Means are provided whereby the cable, as it is wound upon one or the other of the drums 63, 64, will be evenly distributed thereon, and these means are as follows:—

On the end of the shaft 62 is mounted a beveled gear wheel 69, and on the sleeve 65 is mounted a beveled gear wheel 70. The beveled gear wheel 69 engages with the beveled gear wheel 71 on a shaft 72 carried on brackets, such as 73, on one of the side castings, and on the other end of the shaft 72 is mounted a spur pinion 74 which engages a spur wheel 75 also supported in brackets on the side castings. The gear wheel 75 is a skeleton gear wheel, and has attached thereto a link 76, the other end of which is pivotally attached to a block 78 which is arranged to slide freely upon a rod 77 held in the end castings. The block 78 is provided with a downwardly extending bracket carrying a grooved pulley 79 around which the cable passes. The construction for each drum is the same, although oppositely arranged, so that only one need be described. The cable passes over the pulley 79 to the drum 63, and this pulley being moved slowly back and forth by the motion of the wheel 75 the cable is properly distributed in layers upon the drum 63. Of course, the movement of the pulley 79 along the shaft 78 must be so timed that it will cause the cable to be wound up in even layers, and instead of the beveled gear wheels 69 and 71 other forms of transmitting gearing might be used.

80 represents a shaft supported near the upper parts of the castings 59 and 60, and on which the driving pulleys are mounted. On the shaft 80 is loosely mounted a hollow sleeve 81 and a gear wheel 82 which meshes with the gear wheel 66 on the drum 63. On the sleeve 81 is mounted a gear wheel 83 which meshes with the gear wheel 67 on the drum 64. On the shaft 80 and sleeve 81 three pulleys are mounted. The outside pulley 84 is pinned or otherwise fastened to the shaft 80, the middle pulley 85 is loosely mounted on the shaft 80 and the inner pulley 86 is pinned or otherwise fastened to the sleeve 81.

The belt *b*, Fig. 1, is arranged to engage with one of these three pulleys. Obviously when this belt is on the central pulley 83, it will not operate, either of the drums; when it is on the pulley 84 it will operate the shaft 80 and thereby the drum 63, and when it is on the pulley 86 it will operate the sleeve 81 and thereby the drum 64. By this means either the drum 63 or the drum 64 may be positively driven as desired, thus winding the cable *d* in either direction, as desired.

The means for shifting the belt will next be described. Mounted in the casings 59 and 60, at the top thereof, is a transverse

brace rod 87, and parallel to this rod are other brace rods 88 and 89. A brace 90 runs from the shaft 80 to the rod 87, and another brace 91 connects the end of the rod 88 with the end of the shaft 80. Slidably mounted upon the rod 88 is the fork 92 for shifting the belt, which fork is pivotally connected by a link 93 with a handle 94, which is pivotally mounted on a triangular support 95 supported on the rod 88. In the position shown in Fig. 9 the belt is on the loose pulley 85, but if the handle 94 were moved to either end of the support 95, it would shift the belt either to the pulley 84 or to the pulley 86, as desired. Underneath the support 95, and made integral with it, is a downwardly projecting piece 96 at right-angles to the support 95, which carries the means for applying the brakes. 97 represents one of the brake straps, one end of which is attached to the end 98 of the part 96, and the strap then passes around one of the drums 63 or 64, the loose end of the strap being attached at 99 to a bar or link 100, which link is attached to a plate 101. This plate is acted on by eccentrics 102 mounted on a pin 103 in projections on the part 96 and operated by a handle 104.

To prevent the cable from knocking over or injuring the guide pulleys, I make the connection 33 between the cable and the plow detachable. This connection consists of two cylinders 105 and 106, each part having a rounded projection fitting into a depression into the other cylinder, as shown in dotted lines in Fig. 13, and a sleeve 107 held in place by a set screw 108. This connecting part is also provided with an eye 109, which is attached to the chain 34. The cable *d* is held in the cylinder 106 by means of pins 110, 105 which pinch the cable between them.

Each of the guide pulleys, such as *e*, is provided with a segmental guard 111, and if the plow should approach too near the guide pulleys the part 33 would be caught between the pulley and its guard, and the two parts composing the devices 33 would be pulled apart thereby stopping the plow.

The operation is as follows:—The apparatus having been properly adjusted as described, one workman being at the windlass, another on the plow truck, and another at each of the pulleys *e*, *f*, the engine is started. This, by means of the cable *d* pulls one of the plows down, as shown for example in Fig. 3, and as soon as it has been drawn to the lowest possible position, pulls the truck along, plowing the field. When the furrow has been completed the operator at the windlass throws the belt onto the idle pulley and sets the brake. He then releases the brake and throws the belt onto the other pulley, whereupon the truck is drawn in the reverse direction, the first part of said action not advancing the plow truck at all, but merely

- tipping the beam. The operator shifts his position from one of the seats 18 or 19 to the other and turns the guide wheel 28 so as to bring the plow into its proper position.
- 5 When the plow is stopped, by the application of the brakes on the windless drums, the workmen at the pulleys *e* and *f* shift these pulleys so as to keep the cable always in a straight line across the field to be plowed.
- 10 The operation is then repeated indefinitely.

While I have shown only one plow at each end of the plow beam, I do not restrict myself to this arrangement, as it is obvious that a number of plows might be mounted at 15 each end of the beam. The arrangement shown, however, I deem preferable because it is very light and easily worked, requiring only a small engine and the truck attachment of the draft cable renders the apparatus very 20 easy to work.

I claim:—

1. The combination of a wheeled truck, and means for moving the same, with a plow beam mounted thereon, and devices for 25 swinging said plow beam vertically and horizontally, substantially as described.

2. The combination of a truck, a plow beam pivotally mounted thereon, means for adjusting said plow beam vertically, and 30 means for swinging said plow beam horizontally, substantially as described.

3. The combination of a wheeled truck, a plow beam pivotally mounted thereon, means for adjusting said plow beam vertically, 35 means for swinging said plow beam horizon-

tally, and devices whereby a pull upon said truck will cause said plow beam to tilt before the truck is moved, substantially as described.

4. The combination of a wheeled truck, a plow beam pivotally mounted thereon, a cable for moving said truck, and connections between said cable and said truck, including a bent arm, a sliding bar connected to said arm, and connections between said bar and 45 said beam; substantially as described.

5. The combination of a wheeled truck, a plow beam pivotally mounted thereon, a cable for operating said truck, and connections between said truck and said cable, including a bent arm, a sliding bar provided with stops, and connections between said stops and said beam, whereby a pull upon said cable will first lower one end of said plow beam into operative position for plowing and will then move said truck, substantially as described.

6. The combination of a wheeled truck, including a rectangular frame having a central shaft, a plow beam pivotally mounted on 60 said shaft, and a hand wheel gear for adjusting said shaft and said plow beam horizontally, substantially as described.

In testimony whereof I have signed my name to this specification in the presence of 65 two subscribing witnesses.
